UNITED STATES PATENT OFFICE.

ADOLPH N. BRAGSTAD, OF CANTON, SOUTH DAKOTA, ASSIGNOR TO BRAGSTAD CONCRETE MACHINERY CO., INC., OF CANTON, SOUTH DAKOTA, A CORPORATION OF SOUTH DAKOTA.

AUTOMATIC CLEANING-HAMMER.

1,125,950.

Specification of Letters Patent.

Patented Jan. 26, 1915.

Application filed August 18, 1914. Serial No. 857,377.

To all whom it may concern:

Be it known that I, ADOLPH N. BRAGSTAD, a citizen of the United States, residing at Canton, in the county of Lincoln and State 5 of South Dakota, have invented certain new and useful Improvements in Automatic Cleaning-Hammers, of which the following is a specification.

This invention relates to certain new and 10 useful improvements in automatic cleaning hammer for concrete mixing drums.

The primary object of this invention is to provide any of the usual forms of revolving mixing drums with an automatic means for 15 imparting sudden jars thereto, and maintaining the drum clear of the contained material and preventing any clogging thereof.

A further object is to provide a tripping hammer automatically actuated for striking 20 a mixing drum and being simple and inexpensive in its mechanical construction.

It is also designed to provide a hammer traveling by a roller on the hammer and over the surface of the drum and automatically raised for compressing a spring and 25 when tripped violently contacting the drum for cleaning the same of its contents.

With these general objects in view and others that will appear as the nature of the 30 invention is better understood, the same consists in the novel combination and arrangement of parts to be hereinafter more fully described and claimed.

In the drawings forming a part of this 35 application and in which like designating characters refer to corresponding parts throughout the several views, Figure 1 is a side elevational view of the device. Fig. 2 is a transverse sectional view taken through 40 the drum and showing the hammer with parts thereof partially broken away, and Fig. 3 is a perspective view of the lower end portion of the hammer.

Referring more in detail to the drawings, 45 the revolving drum 10 is illustrated herein of substantially the usual construction, being adapted for mixing concrete or similar material, and supported by the framework 11. An encircling band 12 is provided 50 around the drum 10 and constitutes a track or way against which a roller 13 of a hammer head 14 is adapted to ride. The hammer handle 15 which carries the head 14 consists of a metallic rod having its lower end 16 out-

wardly curved while an angular arm or extension 17 laterally projects from one side thereof.

A U-shaped bracket 18 is rigidly mounted upon the frame 11 and is provided with a pivot rod 19, upon which the hammer handle 15 is journaled between the opposite sides of the bracket 18 by having said rod 19 projecting through alining perforations 20 of the handle 15 and extension 17 thereof. A coil spring 21 is linked to the free end of the handle end 16 and is adjustably attached to a strap 22 of an upper portion 23 of the machine frame. Cam plates 24 outwardly project from the surface of the drum 10 and are positioned at one side of 70 the track band 12, the said plates being equally spaced apart peripherally of the drum, and have upwardly inclined face portions 25. A stub shaft 26 projects from the hammer handle 15 upon the side thereof opposite to the extension 17, and is intermediately positioned with respect to the head 14, and the pivot rod 19. A roller 27 is journaled upon the shaft 26 and is positioned for engagement with the cam plates 24 when 80 traveling thereunder.

In operating, the drum 10 revolves in a direction indicated by the arrow in Fig. 2, and the hammer roller 13 normally travels upon the track 12 during such rotation, and 85 is maintained in contact therewith by the normal tension of the spring 21. During such rotation of the drum, the cam plates 24 are successively brought in contact with the side roller 27 of the hammer handle, 90 which roller is thereby made to travel upwardly of the inclined portion 25 of the contacted cam, which elevating of said roller and the adjacent handle end further tensions the spring 21. When the roller 27 reaches the free rearward end 28 of the cam plate, the said roller rides off of the same and by reason of the sudden release of the spring 21, the hammer roller 13 is violently brought into contact with the track 12. It 100 will be evident that as many violent contacts or blows will be administered to the drum by the hammer as there are cam plates provided thereon. This arrangement it will be seen provides an automatic means for 105 raising the hammer from the drum and simultaneously tensioning the operating spring as well as the automatic tripping of

the hammer for successively contacting the hammer in violent blows against the drum which results in agitating the contents of the latter. As will be obvious, under the impacts resulting from the contact between the cams and the roller 27, there will be a lateral thrust exerted upon the hammer 15 which will tend to distort it, and also to transmit a destructive pressure upon the pivot pin 19. To obviate this, and to insure a proper alinement of the hammer handle relative to the cams, the hammer handle is caused to bear against the inner face of one arm of the bracket, while the outer terminal of the arm 17 bears against the other arm of the bracket, and the pivot pin 19 passes through the two bracket arms, the hammer handle and the up-turned end of the arm 17. Under these conditions, any tendency to lateral deflection of the hammer handle, will be prevented, and the strain on the pivot pin will be transmitted to the arm 17 and will thus be equalized.

While the form of the invention herein shown and described is what is believed to be the preferable embodiment, thereof, minor changes may be made without depart-

ing from the spirit and scope of the invention as set forth in the claim.

What I claim as new is:—

In a concrete mixer, the combination with a frame, and a drum revolvably mounted thereon, of spaced cams carried by the drum, a two-armed bracket secured to the frame, a hammer having its handle bearing against the inner side of one of the bracket arms, a roller projecting laterally from one side of the handle in the path of the cams, an arm on the opposite side of the handle and bearing against the inner side of the other bracket arm to brace the handle against yielding from lateral strain due to impact between the roller and the cams, a pivot rod passing through the bracket arms, handle and brace arms, and resilient means for causing the hammer head normally to contact with the drum.

In testimony whereof I affix my signature in presence of two witnesses.

ADOLPH N. BRAGSTAD.
